CLAIM

We claim the ornamental design for a power routing module with ports, as shown and described.

DESCRIPTION

FIG. 1 is a top perspective view of a power routing module with ports, showing our new design;

FIG. 2 is a bottom perspective view thereof;

FIG. 3 is a left side view thereof;

FIG. 4 is a right side view thereof;

FIG. 5 is a front side view thereof;

FIG. 6 is a back side view thereof;

FIG. 7 is a top plan view thereof; and,

FIG. 8 is a bottom plan view thereof.

The broken lines in the drawings depict portions of the power routing module with ports that form no part of the claimed design.
